UNITED STATES PATENT OFFICE.

LOUISE C. KING, OF CLEVELAND, OHIO, ASSIGNOR TO THE F. W. KING OPTICAL COMPANY,
OF CLEVELAND, OHIO, A CORPORATION OF OHIO.

GOGGLES.

1,335,508.

Specification of Letters Patent. Patented Mar. 30, 1920.

Application filed May 31, 1917. Serial No. 171,821.

To all whom it may concern:

Be it known that I, LOUISE C. KING, a citizen of the United States, residing at Cleveland, in the county of Cuyahoga and State of Ohio, have invented a certain new and useful Improvement in Goggles, of which the following is a full, clear, and exact description.

This invention relates to goggles adapted particularly for use by mechanics or workmen in shops, and by automobilists and the like to prevent the eyes being injured by flying particles.

The principal object of the invention is to provide goggles adapted for this purpose and which are strong and rigid, which are comfortable, will be firmly seated on the nose of the wearer, and having a bridge piece which is adjustable but not easily broken.

In carrying out my invention I provide a bridge piece or member which may be composed of one or two parts and which extends between the lens frames or holders, this portion preferably forming a loop or bow adapted to extend across but above the bridge of the nose, and which includes end portions which are secured to, and extend part way around the lens holders forming convex portions adapted to engage and be firmly seated on the sides of the nose, these last named portions being preferably flattened or widened and beveled or inclined rearwardly and laterally so as to form nose engaging portions admirably adapted to properly fit the sides of the nose. This bridge piece is preferably composed of a stiff but flexible material which can be bent to adjust the distance between the nose engaging portions so as to adapt them to the face of the wearer, and when once set or adjusted, will hold the nose engaging portions a proper distance apart.

My invention may be further briefly summarized as consisting in certain novel details of construction and combinations and arrangements of parts which will be described in the specification and set forth in the appended claims.

In the accompanying sheet of drawings, Figure 1 is a perspective view looking toward the rear of goggles constructed in accordance with my invention; Fig. 2 is a rear view of the same with the temples and

shields omitted; Fig. 3 is a sectional view substantially along the line 3—3 of Fig. 2; Fig. 4 is a sectional view substantially along the line 4—4 of Fig. 2; Fig. 5 is a rear view showing a slight modification; Fig. 6 is a top view of the same; Fig. 7 is a section substantially along the line 7—7 of Fig. 5; and Fig. 8 is a sectional view on an enlarged scale, substantially along the line 8—8 of Fig. 7 and Fig. 5.

The goggles constructed in accordance with my invention include lens frames or holders here shown in the form of cups 10, adapted to fit around the eyes, and containing lenses 11. The cups have attached to them, temples 12, which are pivoted in the usual way so that they may be folded across the front of the goggles. Additionally the cups may be provided with shields 13, pivoted at 14 so that they may be folded inwardly across the rear of the cups and adapted to protect the outer corners of the eyes. The lenses 11 may be held in the cups in any desired way such as by having the edges of the lenses extend into grooves of the cups and by flanges bent over in front of the lenses as shown at 10^a in Fig. 4.

The bridge piece and nose engaging member in which my invention resides particularly, is shown at 15. This member includes a bowed portion 15^a and end portions 15^b which lie alongside of and are secured to the cups preferably throughout their length by welding, brazing or soldering. These portions are flattened, being extended laterally toward the rear so that the bowed part 15^a is offset toward the front, and they are beveled or inclined with a rearward lateral curve shown particularly in Fig. 4. These portions 15^b form nose engaging portions which are adapted to rest on the sides of the nose, being convex circumferentially of the cups inasmuch as they follow the curvature of the cups, and being convex transversely of the cups, due to the rearward and lateral bevel so that they slip onto the nose easily and conform to the curvature of the sides of the nose and will rest firmly thereon independently of the upper bowed part which extends well above the bridge of the nose but does not touch the same. The bridge also includes an upper part 15^c which may be integral with, or may be a separate member brazed, soldered or welded to the main

bridge member which is extended downwardly to form the nose engaging portions in the manner described. This part 15^c has branches which extend from the sides of the 5 bowed part over to and are secured to the upper portions of the cups above the arc-shaped sections of the latter which are engaged by the nose engaging portions 15^b.

The bridge piece composed of one or the 10 two parts, as the case may be, is formed of stiff but flexible material so that it can be bent without danger of breakage to vary the distance between the nose engaging portions 15^b whereby they can be adjusted to the face 15 of the wearer, but when once adjusted, they are sufficiently stiff or rigid to hold the cups and the nose engaging portions a proper distance apart.

These goggles above described, are comfortable to wear, they seat firmly on the face 20 of the wearer, and additionally they are not complicated and are therefore not difficult or expensive to manufacture. The upper portion 15^c adds to the rigidity and firmness 25 of the structure but does not prevent the bending of the bridge piece as a whole at the middle thereof to adjust the distance between the nose engaging portions.

In Figs. 5 to 8 I have shown a construction 30 which in its main or essential respects is similar to the construction first described, but is lighter than the first construction, the lens holders, here designated 16, which are substantially in the form of so-called eye 35 wires being narrower and lighter than the cups 10 of the first construction. These lens holders 16 have pivoted to them the corner shields, here designated 17, and temples, here designated 18, and shields and temples 40 being precisely like the shields 13 and temples 12 of the first construction. The bridge piece, here designated 19, differs somewhat from that first described, in the construction or shape of the nose engaging portion. Like 45 the first construction it includes a bowed portion 19^a and the downwardly extending nose engaging portions 19^b adapted to firmly and comfortably seat on the sides of the nose, which portions extend part way around the 50 eye wires in engagement therewith, and are secured thereto. The nose engaging portions 19^b differ from the nose engaging portions 15^b of the construction first described in the respect that they extend rearwardly, or are 55 rearwardly offset to a greater extent than the corresponding portions of the first construction, and are given a different contour. It will be noted by reference particularly to Fig. 7, that the nose engaging portions 19^b 60 are given an irregular curve and have well defined rearwardly extending lobes 19^c, which not only engage the sides of the nose but are designed particularly to protect the

corners of the eyes against flying particles. The nose engaging portions 19^b are in the 65 form of thin webs and throughout or substantially throughout their length are inclined laterally and rearwardly, this bevel or inclination being particularly apparent in Fig. 8. As in the first described construction, the bowed part 19^a has branches 19^d 70 which extend laterally and are secured to the upper portions of the eye wires.

The present construction has all the advantages of the construction first described, 75 and in addition has the feature of lightness explained above.

From the two constructions herein shown and described it will be apparent that my invention may be modified in the details of 80 shape or configuration without departing from the principal features of the invention, and I therefore aim in my claims to cover all modifications which do not involve a departure from the spirit and scope of my invention 85 in its broadest aspects.

Having thus described my invention, what I claim is:

1. Goggles comprising a pair of lens holders containing lenses and a bridge piece 90 composed of a portion extending between the holders, and end portions extending downwardly from said portion part way around the holders and conforming to the shape thereof, said end portions being widened or flattened forming relatively wide 95 rearwardly offset convex supporting members adapted to engage the sides of the nose.

2. Goggles comprising a pair of lens holders or frames containing lenses and a bridge 100 piece which has a bowed portion extending between the holders, and end portions which extend part way around and in conformity with the curvature of the holders and are secured to the holders, said end portions being 105 widened and offset rearwardly with respect to the bowed portion, the widened portions being inclined rearwardly and laterally and forming nose engaging portions adapted to rest on the sides of the nose. 110

3. Goggles comprising a pair of lens holders or frames containing lenses and a stiff flexible bridge piece which has a bowed portion extending between the lens holders, and end portions which extend part way around 115 and are secured to the lens holders throughout the length of the former, said end portions being widened and inclined rearwardly and laterally and forming nose engaging portions adapted to rest on the sides of the 120 nose, the bridge piece having branches which extend to and are secured to the lens holders above the nose engaging portions.

In testimony whereof, I hereunto affix my signature.

LOUISE C. KING.
